UNITED STATES PATENT OFFICE.

ANTON LEDERER, OF ATZGERSDORF, NEAR VIENNA, AUSTRIA-HUNGARY, ASSIGNOR
TO WESTINGHOUSE LAMP COMPANY, OF BLOOMFIELD, NEW JERSEY, A CORPORA-
TION OF PENNSYLVANIA.

INCANDESCENT ELECTRIC LAMP.

971,453.

Specification of Letters Patent. Patented Sept. 27, 1910.

Application filed August 30, 1906. Serial No. 332,721.

To all whom it may concern:

Be it known that I, ANTON LEDERER, a subject of the Empire of Austria-Hungary, residing at No. 83 Atzgersdorf, near Vienna, 5 in the Province of Lower Austria and Empire of Austria-Hungary, have invented certain new and useful Improvements in Incandescent Electric Lamps, of which the following is a specification.

10 The invention relates to the construction of incandescent electric lamps employing fragile filaments such, for instance, as those made of brittle metals, the object being to provide a means for supporting suitable 15 lengths of filament in a convenient manner, reducing, as far as practicable, the liability to breakage.

In the accompanying drawings, Figure 1 is an elevation of a support for the filaments 20 with the filaments in position; Fig. 2 shows the support without the filaments; and Fig. 3 illustrates a modification.

Referring to Figs. 1 and 2, *a* represents the stem of the lamp. It is provided with an 25 extension, *b*, which may be either tubular or solid. Within this extension are placed conducting wires, *h*, *h*, for the electric current. In case the extension is solid these conducting wires will be embedded within the glass 30 or other suitable material forming the support. Guides or supports, *c*, *c*, are provided at proper intervals for anchoring or supporting the filaments, *g*, *g*. The supports *c* are applied to the filaments in any convenient 35 manner. The supports *c* are fastened to the extension *b* by means of wires *d*. At the end of the extension *b* there is fastened a second extension of similar character designed to receive any required number of 40 filaments and it is provided with an extension *e* carrying hooks or supports *c* supported in like manner by wires *d*. Terminal supports *f* are provided for receiving the ends of the filaments which are carried by 45 the last named extension. The leading-in wires, *h*, *h*, are here shown as being so arranged in Fig. 1 as to connect all the filaments in series. In Fig. 2, one of the leading-in wires *h* passes directly to the exten-

sion *e*. It will be understood that various 50 modifications in arrangement of the leading-in wires may be made.

In Fig. 3 an arrangement is shown in which the filaments hang toward the stem of the lamp instead of from the stem as in 55 Figs. 1 and 2.

Filaments arranged according to the manners herein set forth are readily adaptable to being connected in multiple or in series or having their circuit connections changed as 60 required.

I claim as my invention:

1. In an electric lamp, a filament support, a light-giving portion surrounding said support and arranged in lines substantially parallel to its axis, an extension for said support, and a second light-giving portion similarly arranged and surrounding the said extension.

2. In an electric lamp two light-giving 70 portions each arranged in the form of a hollow cylinder, the lines of the filament forming such cylinder being substantially parallel with its axis.

3. In an electric lamp a filament support 75 surrounded by the light-giving portion arranged to form luminous lines substantially parallel with its axis, a second support coaxial with the former and similarly surrounded by a second light-giving portion 80 also arranged to form luminous lines substantially parallel with its axis.

4. In an incandescent electric lamp, the combination of a central supporting stem, a series of incandescent filaments of U- 85 shape form, supports for said filaments at or near one end of the central support, a second series of filaments arranged around an extension of said support in a similar manner, and supports for the second set of 90 filaments located beyond the looped portions of the first series of filaments.

In witness whereof I have hereunto set my hand in presence of two witnesses.

ANTON LEDERER.
